US00D594938S

(12) **United States Design Patent**
Dirneder

(10) **Patent No.:** **US D594,938 S**
(45) **Date of Patent:** **** Jun. 23, 2009**

(54) **HIGH TEMPERATURE DISCONNECT UNION**

(75) Inventor: **Johann Dirneder**, Coldwater (CA)

(73) Assignee: **Praher Canada Products, Ltd.**, Ontario (CA)

(**) Term: **14 Years**

(21) Appl. No.: **29/329,426**

(22) Filed: **Dec. 15, 2008**

Related U.S. Application Data

(62) Division of application No. 29/320,946, filed on Jul. 8, 2008, now Pat. No. Des. 583,026.

(51) **LOC (9) Cl.** **23-01**

(52) **U.S. Cl.** **D23/262**

CLAIM

I claim the ornamental design for a high temperature disconnect union, as shown and described.

DESCRIPTION

FIG. 1 is a front perspective view of my high temperature disconnect union;

FIG. 2 is a rear perspective view of the high temperature disconnect union of FIG. 1;

FIG. 3 is a left-side view of the high temperature disconnect union of FIG. 1;

FIG. 4 is a front view of the high temperature disconnect union of FIG. 1;

FIG. 5 is a rear view of the high temperature disconnect union of FIG. 1; and,

FIG. 6 is a right-side view of the high temperature disconnect union of FIG. 1.

1 Claim, 3 Drawing Sheets
